BONE-CONDUCTION HEARING-AID
VIBRATOR

Hugo Lieber, New York, N. Y., assignor to Lieber
Patents Corporation, New York, N. Y., a cor-
poration of New York

Application July 18, 1933, Serial No. 681,002
Renewed December 29, 1937

13 Claims. (Cl. 179—107)

This invention relates to wearable bone conduction hearing aids and it has among its objects a bone conduction hearing aid utilizing a strip of flexible self-aligning material held stretched along the bony lower rear portion of the head of the user for pressing the vibration imparting contact surface of a bone conduction receiver against the bones of the head and inducing hearing by bone conduction under elimination of the discomfort caused by stiff head bands clamped around the head for pressing the receiver against the bones of the head.

The foregoing and other objects of the invention will be best understood from the following description of exemplifications thereof, reference being had to the accompanying drawings, wherein—

Fig. 1 is a perspective view showing a bone conduction receiver worn on the head of a person in accordance with the invention, and a diagram of the operating circuit of the receiver;

Fig. 2 is a view of the receiver with its supporting elements;

Fig. 3 is an enlarged sectional view of the receiver along lines 3—3 of Fig. 5;

Fig. 4 is a top view of the receiver;

Fig. 5 is a vertical sectional view of the receiver;

Fig. 6 is a detailed enlarged view of an ear clasp of the receiver support;

Fig. 7 is a view similar to Fig. 2 of a modified receiver support;

Fig. 8 is a top view of the support shown in Fig. 7;

Fig. 9 is a view of the receiver with its support illustrating a further modification of the invention;

Fig. 10 is a top view of the support shown in Fig. 9;

Fig. 11 is a perspective view illustrating a modified receiver support of the invention;

Fig. 12 is a top view of one of the arrangements shown in Fig. 11;

Fig. 13 is a view similar to Fig. 12 showing a further modification of the invention; and

Fig. 14 is a view similar to Fig. 7 illustrating a still further modification of the invention.

Referring to the exemplification of the invention shown in Figs. 1 to 6, it comprises a bone conduction receiver, of the type disclosed in Greibach Patent 2,127,468, in the form of a small vibratory casing 20 having actuating windings 21 which are connected to a supply circuit formed of a transmitter 22 connected in series with a supply battery 23 to the actuating coil 24 of an

amplifier microphone 25 which is connected in series with the battery 23 to the leads 26 which supply the current to the actuating windings 21 of the receiver, all constructed for inconspicuous wear by the user. Under the action of the supplied electric sound frequency oscillations, the floating part of the vibratory structure 27 imparts through its inertia reaction hearing inducing vibratory forces to the casing 20, and by way of its contact wall 28 to the hearing inducing bones 29 of the user for inducing hearing by bone conduction.

As shown in Figs. 1 to 4, the vibratory surface of the receiver casing 20 is held coupled to the mastoid bone 29 of the user, behind the ear, by supporting arrangements comprising a pair of ear clasps 31, 32 and a strip 33 of self-aligning flexible material, such as rubber fabric, which are interconnected with the receiver 20 so as to hold a contact surface 28 of the receiver 20 against the mastoid bone.

As shown in Fig. 1, the flexible self-aligning supporting strip 33 extends over the occipital bone of the head below the greater occipital protuberance and the clasps 31, 32 which hold the strip 33 in the stretched condition engage portions of the head at the junction of the auricle to the head in the region of the temporal bones. Such arrangement of the stretched strip and its stretching means which hold it in stretched condition make it possible to retain the stretched strip 33 in a self-aligning position on the lower region of the back of the head in which it is able to exert on the bone conduction receiver the pressure required for transmitting to the bones 30 hearing inducing vibrations without discomfort to the user.

The ear clasp 31 is made in the form of an oval wirelike member shaped to fit the groove along the rear side of the junction of the auricle to the head. The clasp 31 is retained in its place on the ear by front portions 37 overlapping the junction portions of the auricle to the head so as to firmly and yet gently support the clasp 31 on the ear and prevent its being pulled off the ear by rearwardly directed forces acting on the intermediate portion of the clasp 31. The center portion of the clasp 31 has a pin shaped projection 35 fitting into a longitudinal channel member 36 provided along one edge of the vibratory receiver casing 20 for holding the receiver. The other side of the receiver casing 20 has an eyelet 41 to which is tied one end of the self-aligning supporting strip 33 the other end of which is held in an eyelet 40 formed on the 40 45 50 55 60 65 70 75 80 85 90 95 100

center portion of the similar other ear clasp 32 which engages the other ear.

The supporting strip 33 may be of rubber or similar resilient material, covered with a woven fabric, such as silk, and is arranged to lie snugly in stretched condition against the head, hidden under the hair, as shown in Fig. 1. The length of the supporting strip 33 is so proportioned that when it is held stretched by the ear clasps 31, 32, the contact surface 28 of the receiver casing 20 will be held against the bones 29 with the pressure required for securing efficient transmission of the hearing inducing vibrations from the contact wall 28 of the receiver casing 20 to the bone structure.

The end portions of the ear clasps 31, 32 may be made of a resilient metal wire as shown in Fig. 6 and comprise several layers 43, 44, 45 of wire strands closely wound over the wire of the clasp, in a way similar to temple wires of spectacle frames, so as to secure a good gripping connection between the clasp ends and the engaged auricle portions and permit easy adjustment of the clasp to the shape of the auricle. The clasps 31, 32 may be made of any suitable metal and the ends overlapping the auricle and resting against it may be provided with a resilient layer 47 of rubber or like material to distribute the pressure over the contact surface. The resilient engagement of the clasp pin 35 with the receiver channel 36 is so arranged as to assure alignment of the receiver relatively to the surface of the bones and good coupling engagement therebetween.

By utilizing a strip of flexible self-aligning fabric material which is held stretched over the rear of the head, below its greater occipital protuberance, by clasp means which engage the portions of the head in the region of the temporal bones so as to exert on the receiver casing forces which hold it in intimate vibration transmitting contact engagement with the bones of the head, the receiver support will be automatically retained in a self-aligning vibration transmitting position and assure efficient transmission of the hearing inducing vibrations to the bones of the head.

In Figs. 7 and 8 is shown a modified bone receiver supporting arrangement. It comprises a relatively rigid, slightly flexible, U-shaped supporting frame member 51 having inward protuberances 52 engaging suitable depressions in the side walls of the receiver casing. One of the arms of the frame 51 is provided with a longitudinal eyelet 53 which is engaged by the central portion of an ear clasp 31 similar to the ear clasp of Fig. 2. The other arm of the receiver supporting frame 51 is provided with an eyelet 54 to which is tied one end of a flexible self-aligning supporting strip 33, the other end of which is tied to the other similar ear clasp 32 so as to support the receiver frame 51 in a position in which it presses the contact surface of the receiver casing against the hearing inducing bones. The clasp 31 is resiliently mounted within the channel member 53 of the receiver frame 51 so as to be free to turn and provide a self-adjustable support for the receiver casing. The pivotal mounting of the receiver casing on the pivot pins 52 of the receiver frame 51 assures automatic alignment of the contact surface of the receiver 20 against the bones.

As shown in Fig. 8, the vibratory receiver casing 20 is provided with a channel 56 for receiving the end of a head band so as to enable the user

to wear the receiver either with the stretchable strip support arrangement shown in the drawings or by means of a steel head band clamped over the head. The frame 51 has sufficient resiliency to permit spreading apart of its arms 5 and removal of the receiver 20 from its supporting pin 52.

In Figs. 9 and 10 is shown a bone receiver supporting arrangement similar to that of Figs. 7 and 8, but using a different form of U-shaped receiver supporting frame 58 arranged to embrace one of the narrow end walls of the receiver.

In Figs. 11 and 12 is shown another form of bone receiver support by a flexible self-aligning fabric strip 33. The receiver is pivotally mounted on a frame 51 as in the arrangement of Fig. 7. The channel-shaped eyelet 53 of the frame is engaged by an end portion of a modified form of clasp 61 formed of metal or similar material and arranged to embrace only the upper junction of 20 the auricle to the head. The clasp 61 comprises a front arm 62 and a rear arm 63 embracing the upper portion of the auricle edge adjacent its junction to the head, the front end 64 of the clasp being bent to fit into the cavity behind the 25 upper helix portion 65 of the auricle. The rear part of the clasp 61 extends along the rear portion of the auricle and terminates in a pivotal pin portion held in the channel member 53 provided on one arm of the receiver supporting 30 frame 51. The two ends of the stretched supporting strip 33 extending along the back of the head are joined to the eyelet 54 of the receiver supporting frame, and to an eyelet 67 provided on the rear end of a clasp 68 shaped similarly 35 to the clasp 61, and engaging the auricle of the other ear, so as to secure self-aligning support of the receiver in contact with the bones of the head.

In Fig. 13 is shown a modified form of ear 40 clasp 70 of the type shown in the arrangement in Figs. 10 and 11. The clasp 70 is made of a relatively rigid, slightly yieldable strip of metal or similar material and has a front arm 71 embracing the helix 72 of the upper auricle junction 45 to the head and an enlarged rear arm portion 73 having a threaded hole in which is threaded 50 mounted a fastener screw 74 provided with a contact member 75 for clamping the clasp to the ear.

In the modified form of the bone receiver support shown in Fig. 14, two ear clasps 68, similar to the ear clasps of the arrangement shown in Figs. 11 and 12, hold stretched two strip portions 77 of flexible self-aligning fabric material across 55 the rear of the head below the occipital protuberances for coupling to the bones a bone receiver 20 held between the two strip portions 77, for instance, by a clamp support 51, of the type shown in connection with Figs. 7 and 8.

The exemplifications of the invention described above will suggest to those skilled in the art many other ways for holding the contact surface of a bone conduction receiver in vibration transmitting coupling engagement with the hearing inducing bones of the user, by means of a strip of self-aligning flexible material held stretched along the rear side of the bony skull and head below the greater occipital protuberance for 70 inducing hearing by bone conduction without the discomfort accompanying the use of a head band clamped over the head of the person for supporting a bone conduction receiver. It is accordingly desired that the appended claims be 75

given a construction commensurate with the scope of the invention.

Some of the features of the invention constitute the subject matter of a divisional application.

5 I claim:

1. In a bone-conduction hearing-aid device, a bone conduction receiver of small size and weight having a vibratory contact surface for engaging hearing inducing bone structure on the head of a person and converting received electric sound-frequency oscillations into corresponding hearing-inducing mechanical vibrations imparted to said bone structure, means for supporting said receiver on the head of a person with the contact surface pressed against the bone structure of the head comprising clamp means extending over each ear of the person embracing the auricle of the ear from the rear side thereof and overlapping with forwardly extending portions the upper junction portions of the auricles to the head for preventing said clasp means from being pulled off the head by rearward pull, and a strip-like connector of flexible self-aligning material connected between the rear sides of said clasp means to lie stretched against the back portion of the head below its greater occipital protuberance and press against it, said receiver being held by said connector and pressed with its vibratory contact 30 surface against a portion of the bone structure of the head by the stretching force in said connector.

2. In a bone-conduction hearing-aid device, a bone conduction receiver of small size and weight having a vibratory contact surface for engaging hearing-inducing bone structure on the head of a person and converting received electric sound-frequency oscillations into corresponding hearing-inducing mechanical vibrations imparted to said bone structure, means for supporting said receiver on the head of a person with the contact surface pressed against the bone structure of the head comprising clasp means for each ear of the person embracing the auricle of the ear from the rear side thereof and overlapping with forwardly extending portions the upper junction of the auricles to the head for preventing said clasp means from being pulled off by rearwardly directed forces, and a strip-like connector of flexible self-aligning material connected between the rear sides of the two clasps to lie stretched against the back portion of the head and press against it, said receiver unit being held by said connector and pressed with its vibration transmitting contact surface against a portion of the bone structure of the head by the stretching force in said connection.

3. In a bone-conduction hearing-aid device, a bone conduction receiver of small size and weight having a vibratory contact surface for engaging hearing-inducing bone structure on the head of a person and converting received electric sound-frequency oscillations into corresponding hearing-inducing mechanical vibrations imparted to said bone structure, means for supporting said receiver on the head of a person with the contact surface pressed against the bone structure of the head comprising clasp means for each ear of the person embracing the auricle of the ear from the rear side thereof and overlapping with forwardly extending ends the upper junction of the auricle to the head and prevented thereby from being pulled off the ear by rearwardly directed forces acting on the clasp, said receiver having one side thereof attached to the rear portion of one of said clasps in a position at which the

vibratory contact surface of said receiver engages the outer surface of the sound conducting bone structure of the head lying opposite the convex rear side of the auricle, and a strip-like connector of flexible self-aligning material having one end connected to the side of vibrator unit lying opposite the side attached to said clasp, the opposite end of said connector being connected to the rear side of the other clasp to lie in stretched condition against the back portion of the head and to hold in conjunction with the clasp attached to the receiver unit the contact surface thereof under pressure against the engaged bone structure.

4. In a bone-conduction hearing-aid device, a bone conduction receiver of small size and weight having a vibratory contact surface for engaging hearing-inducing bone structure on the head of a person and converting received electric sound-frequency oscillations into corresponding hearing-inducing mechanical vibrations imparted to said bone structure, means for supporting said unit on the head of a person with the contact surface pressed against the bone structure of the head comprising clasp means for each ear of the person embracing the auricle of the ear from the rear side thereof and overlapping with forwardly extending slightly-yielding elastic ends the upper and lower junction portions of the auricle to the head and prevented thereby from being pulled off the ear by rearwardly directed forces acting on the clasp, said receiver unit having one side thereof attached to the rear portion of one of said clasps in a position at which the vibratory contact surface of said unit engages the outer surface of the mastoid bone structure of the head lying opposite the convex rear side of the auricle, and a self-aligning flexible strip having one end connected to the side of said receiver unit lying opposite the side attached to said clasp, the opposite end of said strip being connected to the rear side of the other clasp to lie in stretched condition against the back portion of the head and to hold in conjunction with the clasp attached to the receiver the contact surface thereof under pressure against the engaged bone structure.

5. In a bone-conduction hearing-aid device, a bone conduction receiver comprising a casing enclosing a vibrator mechanism for converting received electric sound-frequency oscillations into corresponding hearing-inducing mechanical vibrations imparted to an element constituting a contact surface on the exterior wall of said casing for transmitting said vibrations to hearing-inducing bone structure of a person engaged under pressure through said contact surface and inducing sound in the auditory center of the person, means for supporting said casing on the head of a person with the contact surface pressed against the bone structure of the head comprising clasp means for each ear of the person for embracing the auricle of the ear from the rear side thereof and overlapping with forwardly extending portions the upper junction of the auricle to the head and prevented thereby from being pulled off the ear by rearwardly directed forces acting on the clasp, and a self-aligning flexible connector strip connected between the rear sides of the clasp means to lie stretched against the back portion of the head below its greater occipital protuberance and press against it, said receiver being held by said connector and pressed with its vibration transmitting contact surface against a

portion of the bone structure of the head by the stretching force in said connector strip.

6. In a bone-conduction hearing-aid device, a bone conduction receiver comprising a casing enclosing a vibrator mechanism for converting received electric sound-frequency oscillations into corresponding hearing-inducing mechanical vibrations imparted to an element constituting a contact surface on the exterior wall of said casing for transmitting said vibrations to hearing-inducing bone structure of a person engaged under pressure through said contact surface and inducing sound in the auditory center of the person, means for supporting said casing on the head of a person with the contact surface pressed against the bone structure of the head comprising a clasp for each ear of the person for embracing the auricle of the ear from the rear side thereof and overlapping with forwardly extending slightly-yielding elastic ends the upper and lower junction portions of the auricle to the head and preventing thereby from being pulled off the ear by rearwardly directed forces acting on the clasp, said receiver casing having one side thereof attached to the rear portion of one of said clasps in a position at which the vibratory contact surface of said casing engages the outer surface of the mastoid bone structure of the head lying opposite the convex rear side of the auricle, and a flexible self-aligning strip having one end connected to the side of the casing lying opposite the side attached to said clasp, the opposite end of said cord being connected to the rear side of the other clasp to lie in stretched condition against the back portion of the head and to hold in conjunction with the clasp attached to the casing the contact surface thereof under pressure against the engaged bone structure.
7. In a bone-conduction hearing-aid device, a bone conduction receiver of small size and weight having a vibratory contact surface for engaging hearing-inducing bone structure on the head of a person and converting received electric sound-frequency oscillations into corresponding hearing-inducing mechanical vibrations transmitted through said contact surface to said bone structure to induce hearing in the auditory center of the person, means for supporting said receiver on the head of a person with the contact surface pressed against the bone structure of the head comprising a clasp for each ear of the person having two integrally connected substantially C-shaped members, one member being positioned to engage over one portion of the ear of the user and the other member being positioned to engage another portion of the ear to increase the pressure of said first member and grip said ear portion between said members to prevent pulling off the clasp from the ear by rearwardly directed stretching forces acting on the clasp, and a strip-like connector of flexible self-aligning material connected between the rear arms of the two clasps to lie stretched against the back portion of the head and press against it, said receiver unit being held by said connector and pressed with its vibration transmitting contact surface against a portion of the bone structure of the head by the stretching force in said connection.
8. In a bone-conduction hearing-aid device, a bone conduction receiver of small size and weight having a vibratory contact surface for engaging hearing-inducing bone structure on the head of a person and converting received electric sound-frequency oscillations into corresponding hearing

inducing mechanical vibrations transmitted through said contact surface to said bone structure to induce hearing in the auditory center of the person, means for supporting said receiver on the head of a person with the contact surface pressed against the bone structure of the head comprising a clasp for each ear of the person for embracing the upper edge portion of the auricle of the ear adjacent its junction to the head, said clasp having a front arm overlapping and engaging the front side of the auricle edge at its upper junction with the head, and an adjoining rear arm extending behind the ear to prevent pulling off the clasp from the ear by rearwardly directed stretching forces acting on the clasp, and a strip-like connector of flexible self-aligning substance connected between the rear arms of the two clasps to lie stretched against the back portion of the head and press against it, said receiver being held by said connector and pressed with its vibration transmitting contact surface against a portion of the bone structure of the head by the stretching force in said connection.

9. In a bone-conduction hearing-aid device, a bone conduction receiver of small size and weight having a vibratory contact surface for engaging hearing-inducing bone structure on the head of a person and converting received electric sound-frequency oscillations into corresponding hearing-inducing mechanical vibrations transmitted through said contact surface to said bone structure to induce hearing in the auditory center of the person, means for supporting said receiver on the head of a person with the contact surface pressed against the bone structure of the head comprising a clasp for each ear of the person for embracing the upper edge portion of the auricle of the ear adjacent its junction to the head, said clasp having a front arm overlapping and engaging the front side of the auricle edge at its upper junction with the head, and an adjoining rear arm overlapping the adjacent rear side of the embraced auricle edge to prevent pulling off the clasp from the ear by rearwardly directed stretching forces acting on the clasp, said receiver having one side thereof attached to the rear arm of one of said clasps in a position at which the vibratory contact surface of said unit engages the outer surface of the sound conducting bone structure of the head lying opposite the convex rear side of the auricle, and a strip-like connector of flexible self-aligning substance having one end connected to the side of said receiver lying opposite the side attached to said clasp, the opposite end of said connector being connected to the rear side of the other clasp to lie in stretched condition against the back portion of the head and to hold in conjunction with the clasp attached to said receiver the contact surface thereof under pressure against the engaged bone structure.

10. In a bone-conduction hearing-aid vibrator, a bone conductor receiver comprising a casing enclosing a vibrator mechanism for converting received electric sound-frequency oscillations into corresponding mechanical vibrations imparted to an element constituting a substantially flat contact surface on the exterior wall of said casing for transmitting said vibrations to sound conducting bone structure of a person engaged under pressure by said contact surface and inducing sound in the auditory center of the person, holder means for supporting said casing on the head of a person with the contact surface pressed against the bone structure of the head comprising a clasp for each ear of the person embracing the auricle of the ear

- from the rear side thereof and overlapping with forwardly extending ends the upper and lower junction portions of the auricle to the head and prevented thereby from being pulled off the ear by rearwardly directed forces acting on the clasp, said casing having one side thereof attached to the rear arm of one of said clasps in a position at which the vibratory contact surface of said casing engages the outer surface of the sound 10 conducting bone structure of the head lying opposite the convex rear side of the auricle, and a strip-like connector of flexible self-aligning substance having one end connected to the side of the casing lying opposite the side attached to said 15 clasp, the opposite end of said connector being connected to the rear side of the other clasp to lie in stretched condition against the back portion of the head and to hold in conjunction with the clasp attached to the casing the contact surface 20 thereof under pressure against the engaged bone structure.
11. In a bone-conduction hearing-aid device, a bone conduction receiver of small size and weight having a vibratory contact surface for engaging 25 hearing-inducing bone structure on the head of a person and converting received electric sound-frequency oscillations into corresponding hearing-inducing mechanical vibrations transmitted through said contact surface to said bone structure to induce hearing in the auditory center of the person, means for supporting said receiver on the head of a person with the contact surface pressed against the bone structure of the head comprising a clasp for each ear of the person for 30 embracing the upper edge portion of the auricle of the ear adjacent its junction to the head, said clasp having a front arm overlapping and engaging the front side of the auricle edge, and an adjoining rear arm overlapping the adjacent rear 35 side of the embraced auricle edge to prevent pulling off the clasp from the ear by rearwardly directed stretching forces acting on the clasp, and a strip-like connector of flexible self-aligning substance connected between the rear arms of the 40 two clasps to lie stretched against the back portion of the head and press against it, said receiver being held by said connector and pressed with its vibration transmitting contact surface against a portion of the bone structure of the head lying 45 about midway the distance between the ears by the stretching force in said connection.
12. In a bone-conduction hearing-aid device, a bone conduction receiver of small size and weight having a vibratory contact surface for engaging 50 hearing-inducing bone structure on the head of a person and converting received electric sound-frequency oscillations into corresponding hearing-inducing mechanical vibrations transmitted through said contact surface to said bone structure to induce hearing in the auditory center of the person, means for supporting said receiver on the head of a person with the contact surface 55
- pressed against the bone structure of the head comprising a frame having a pair of arms engaging the opposite sides of said receiver for holding the contact surface of said receiver in engagement with the bone structure of the person, supporting brackets on said arms, a clasp for each ear of the person for embracing an edge portion of the auricle of the ear adjacent its junction to the head, said clasp having a front arm overlapping and engaging the front side of the auricle edge, and an adjoining rear arm overlapping the adjacent rear side of the embraced auricle edge to prevent pulling off the clasp from the ear by 60 rearwardly directed stretching forces acting on the clasp, and a strip-like connector of flexible self-aligning substance connected between the rear arms of the two clasps to lie stretched against the back portion of the head and press against it, said supporting brackets being held by said connector to apply stretching forces to said frame for pressing the vibration transmitting surface of said receiver against the bone structure.
13. In a bone-conduction hearing-aid device, a bone conduction receiver comprising a casing enclosing a vibrator mechanism for converting received electric sound-frequency oscillations into corresponding hearing-inducing mechanical vibrations imparted to an element constituting a substantially flat contact surface on the exterior 25 wall of said casing for transmitting said vibrations to hearing-inducing bone structure of a person engaged under pressure through said contact surface and inducing sound in the auditory center of the person, means for supporting said 30 casing on the head of a person with the contact surface pressed against the bone structure of the head comprising a frame having a pair of arms pivotally engaging the opposite sides of said vibrator casing for adjustably holding the contact 35 surface of said receiver in engagement with the bone structure of the person, supporting brackets on said arms, a clasp for each ear of the person for embracing an edge portion of the auricle of the ear adjacent its junction to the 40 head, said clasp having a front arm overlapping and engaging the front side of the auricle edge, and an adjoining rear arm overlapping the adjacent rear side of the embraced auricle edge to prevent pulling off the clasp from the ear by 45 rearwardly directed stretching forces acting on the clasp, and a strip-like connector of resilient stretchable substance connected between the rear arms of the two clasps to lie stretched against the back portion of the head and press 50 against it, said supporting brackets being held by said connector to apply stretching forces to said frame for pressing the vibration transmitting surface of said receiver against the bone structure.

HUGO LIEBER.
